US00D498511S

(12) **United States Design Patent** (10) Patent No.: **US D498,511 S**
Warren et al. (45) Date of Patent: **** Nov. 16, 2004**

(54) **WATER FILTER**

(75) Inventors: **William Warren**, Shaker Heights, OH (US); **Gordon Lewis**, Needham, MA (US); **Robert Rizzari**, Billerica, MA (US); **Louis F. Genatossio**, Shrewsbury, MA (US)

(73) Assignee: **Clear Flow Corporation**, Needham, MA (US)

(**) Term: **14 Years**

(21) Appl. No.: **29/185,840**

(22) Filed: **Jul. 3, 2003**

(51) LOC (7) Cl. **23-01**

(52) U.S. Cl. **D23/209**

(58) Field of Search D23/207, 209; 210/460, 418, 428, 449

Primary Examiner—Robin V. Taylor

(74) Attorney, Agent, or Firm—Woodling, Krost and Rust

(57) **CLAIM**

The ornamental design for a water filter, as shown and described.

DESCRIPTION

FIG. 1 is a perspective view of our design.

FIG. 2 is a front view of our design.

FIG. 3 is a left side view of our design.

FIG. 4 is a right side view of our design.

FIG. 5 is a top view of our design.

FIG. 6 is a bottom view of our design; and,

FIG. 7 is a rear view of our design.

1 Claim, 4 Drawing Sheets

FIG. 2

FIG. 1

FIG. 4

FIG. 3

FIG. 6

FIG. 5

FIG. 7

UNITED STATES PATENT AND TRADEMARK OFFICE
CERTIFICATE OF CORRECTION

PATENT NO. : Des. 498,511 S
DATED : November 16, 2004
INVENTOR(S) : Warren et al.

Page 1 of 3

It is certified that error appears in the above-identified patent and that said Letters Patent is hereby corrected as shown below:
